Primary Examiner — Calvin E Vansant*Assistant Examiner* — Cheng Chen(74) *Attorney, Agent, or Firm* — Larson & Larson; Frank Liebenow; Justin P. Miller(57) **CLAIM**

The ornamental design for a handheld propulsion control device, as shown and described.

DESCRIPTION

FIG. 1 is a perspective view of a handheld propulsion control device showing my new design

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof; and,

FIG. 7 is a bottom plan view thereof.

Portions of the handheld propulsion control device shown in broken lines form no part of the claimed design.
